UNITED STATES PATENT OFFICE

FRED C. KING, OF PORTLAND, OREGON

BURIAL VAULT

Application filed July 25, 1928. Serial No. 295,194.

This invention relates generally to burial vaults, and particularly to a special form of an all metal self-sealing vault.

The main object of this invention is to provide an exceedingly simple form of vault and to provide a special form of closing mechanism therefor which will insure the base of the vault being locked rigidly to the top thereof when so desired when the parts are duly joined together.

The second object is to so construct the vault that the parts when once assembled will be extremely rigid and not easy to get out of order.

These, and other objects, will become more apparent from the specification following as illustrated in the accompanying drawing, in which:

Figure 1 is a perspective view of an assembled vault. Figure 2 is a perspective view of the bottom of a vault. Figure 3 is a section taken along the line 3—3 in Figure 1 showing the latch engaged. Figure 4 is a view similar to Figure 3 but showing the latch held out of engagement. Figure 5 is a section taken along the line 5—5 in Figure 1. Figure 6 is a section taken along the line 6—6 in Figure 1. Figure 7 is a detail of the latch. Figure 8 shows an alternative form of handle connection. Figure 9 shows an alternative form of raised portion on the bottom of the base.

Similar numbers of reference refer to similar parts throughout the several views.

Referring in detail to the drawing, the vault itself consists of two principal parts, namely a base and a cover. The base consists of a raised central portion 10 whose side walls 11 are provided with the outwardly turned flanges 12, the parts preferably consisting of sheet metal suitably welded together.

At opposite sides of the base and secured to the flanges 12 are the handles 13, by means of which the vault is raised or lowered. At each corner of the vault and secured to the side walls 11 are the latch springs 14 whose latches 15 can project through the openings 16 in the wall 11. Each latch is also provided with a hole 17

18 when the latch is withdrawn (as shown in Fig. 4) for the purpose of inserting a nail 19.

In the central portion 10 of the base is formed a plurality of projections 20 on which the casket rests. These may be in the form of a frustum of a cone.

The cover consists of the sides 21 whose upper portions unite to form a curved top 22, across which sides and top are secured the ends 23. The lower edges 24 of the sides 21 and ends 23 are provided with inwardly and upwardly turned flanges 25 which are of a height to permit them to pass under the side 26 of the latch 15 when the edges 24 rest upon the flanges 12.

It is desirable to provide handles 27 along each of the sides 21, these usually being in the form of a continuous rod supported at intervals by the brackets 28, which themselves are secured in pairs to a sub-base 29 which, in turn, is secured to the side 21.

In the alternative form shown in Fig. 8 the bracket 30 is secured directly to the side 21 by allowing the tongue 31 of the bracket 30 to project through an opening in the sides 21 and then welding the member 30 in position (as shown).

Where the sub-bases 29 are employed it is desirable to form the inwardly turned flanges 32 therein which attach the sides 21 and then filling in the openings by means of a weld 33, forming a very secure and workmanlike connection.

In the form of the device shown in Figure 9, instead of having a number of projections 20 (as shown in Fig. 2) there are formed the long narrow projections 34 which have the advantage that they form a stiffener for the member 10.

I am aware that many forms of metal burial vaults have been constructed in the past; it is therefore not my desire to cover such devices broadly, but I do intend to cover all such forms and modifications thereof as fall fairly within the appended claim.

I claim:

A burial vault having in combination an

elevated base having upright side walls and horizontal outwardly extending lower edges, a plurality of latches disposed around said side walls above said outwardly turned edges, each of said latches consisting of a flat spring secured on the inner side of said elevated base having a latch formed on each end thereof projecting freely through the side wall of said base giving access to said spring from the under side of said base, means for holding said latch in a retracted position consisting of a pin passing through the top of said base into said latch member, a cover for said vault having vertical side walls and an upwardly turned **U**-shaped bottom edge, the innermost portion of said edge forming a shoulder for engagement with said latch, and the lowermost portion of said edge normally resting upon said outwardly turned base edge.

FRED C. KING.
